DESIGN.

E. L. CALEY & J. A. READ.
PORTABLE FIRE PLACE GRATE.

No. 19,148.

Patented June 11, 1889.

UNITED STATES PATENT OFFICE.

EDWARD L. CALEY AND JOSEPH A. READ, OF PHILADELPHIA, PENNSYLVANIA, ASSIGNORS TO GILBERT COMBS, JOIN BAWDEN, AND JOHN H. BAWDEN, OF FREEHOLD, NEW JERSEY.

DESIGN FOR A PORTABLE FIRE-PLACE GRATE.

SPECIFICATION forming part of Design No. 19,148, dated June 11, 1889.

Application filed January 9, 1889. Serial No. 295,880. Term of patent 7 years.

To all whom it may concern:

Be it known that we, EDWARD L. CALEY and JOSEPH A. READ, citizens of the United States, and residents at Philadelphia, Pennsylvania, have invented a certain new and original Design for a Fire-Place Grate, of which the following is a specification.

Our design for a fire-place grate is fully shown in the accompanying photographic illustration.

The leading features of the design are the ornamental vertical bars on the front, back, and side plates, and the ornamental scroll-work on the back and side plates below said bars. On the lower half of the back plate is a quadrangular panel with plain border-lines with scalloped corners, and on this panel is a central foliated ornament, from which extend two plain scrolls and two ornamental floral scrolls. Above the panel are a series of vertical bars, forming open-work, and on each of these bars are ornamental designs and a central rosette.

The design of the side-plate panels and bars is in keeping with those of the back plate.

The design of the front plate is composed of top and bottom longitudinal bars connected

together by ornamental vertical bars with central rosettes and other ornamentation of the same general character as the bars of the back plate.

We claim—

1. In a design for a fire-place grate, the design for the back plate, consisting of the quadrangular foliated and scroll panel, with a series of vertical figured bars above said panel, substantially as described, and as shown in the accompanying photographic illustration.

2. In a design for a fire-place grate, the design for the front plate, consisting of a series of vertical figured bars, substantially as described, and as shown in the accompanying photographic illustration.

3. The design for a fire-place grate, substantially as described, and as shown in the accompanying photographic illustration.

In testimony whereof we have signed our names to this specification in the presence of two subscribing witnesses.

EDWARD L. CALEY.
JOSEPH A. READ.
